UNITED STATES PATENT OFFICE.

DAVID BOORMAN, OF ALTOONA, PENNSYLVANIA.

SHAFT-COUPING.

SPECIFICATION forming part of Letters Patent No. 503,033, dated August 8, 1893.

Application filed March 25, 1893. Serial No. 467,570. (No model.)

To all whom it may concern:

Be it known that I, DAVID BOORMAN, of Altoona, in the county of Blair and State of Pennsylvania, have invented certain new and useful Improvements in Shaft-Couplings; and I do hereby declare the following to be a full, clear, and exact description of the invention, such as will enable others skilled in the art to which it appertains to make and use the same.

10 This invention relates to an improvement in shaft-couplings, the object being to provide a simple and inexpensive arrangement of parts which can be quickly coupled, tightened, loosened or uncoupled, and is designed 15 more particularly as an improvement on my Patent No. 432,364, granted me July 15, 1890.

My invention consists in certain novel features of construction and combinations of parts as will be hereinafter more fully described and pointed out in the claims.

In the accompanying drawings Figure 1 is a view in longitudinal section through the coupling collar and two of the keys, the ends of the shafts appearing in elevation. Fig. 2 25 is a view in transverse section through the shaft showing the coupling and keys in end elevation. Fig. 3 is a view in perspective of one of the keys. Fig. 4 is a view in side elevation of a modified form of collar showing 30 the internal formation in dotted lines. Fig. 5 is a view in end elevation of this modified form of collar, and Fig. 6 is a modified form of collar.

A and B represent a pair of shafts, the ends 35 of which are provided with a series of key-seats b. The depth of the latter decreases gradually as they extend toward the ends of the shafts thus giving them a tapering form, as shown.

40 C is a collar, the center of which is bored to receive the ends of shafts A, B, and is provided with a series of key-seats a extending straight through from one end of the collar to the other end. When the ends of the shafts A, B, are 45 inserted in the collar the key-seats in the two shafts are made to register with the key-seats in the collar, and the openings formed by such key-seats are adapted to receive suitable keys.

D, D', represent the keys, the former being 50 longer than the latter, and adapted when in its normal or locked position in the key-seats

to project beyond the juncture of the shafts A, B, whereby the longer key locks the ends of both shafts.

The keys D, D', are preferably of the form 55 shown in Fig. 3, each of which is provided with a horizontal bolt hole c adapted to receive and accommodate the bolt E, by means of which the keys D, D', are tightened or loosened as desired.

60 The ends of the collar are preferably flanged so that the ends of the keys and bolts together with the nuts are protected. When the parts are assembled, the nuts on bolts E are screwed home and the shafts are thus securely held 65 together and prevented from turning.

The bottom or inclined faces of keys D, D', are made to conform to the shape of the tapering key-seats b of shafts A, B, and when the former are tightened by the bolts E, it will 70 readily be seen that the keys D, D', will travel toward each other and securely lock the shafts against movement and also lock the keys against endwise movement. When the keys are constructed in one piece it sometimes happens that the pressure on both shafts is not 75 equal and consequently one shaft is liable to have slight play, but by constructing the keys as above described, this difficulty is obviated. By turning the nut on bolt E it will be seen 80 that the keys D, D', travel up the oppositely inclined faces of the key-seats b toward each other and consequently firmly lock the shafts A, B, together.

I might in some instances use keys of the 85 same length instead of making them of unequal lengths as shown, and I can also if desired dispense with key-seats on the shafts and form tapering key-seats in the collar as clearly shown in Fig. 5. With this latter construction, it will not be necessary where the shafts have but light work to perform to form seats of any kind in the shafts, but it is evident, if I so desire, that I can simply flatten the surfaces of the shafts against which the 90 keys rest and then positively overcome any tendency of either section to turn. Again if I so desire I can as shown in Fig. 6 provide one or both sections of each key with female threads with which a bolt passing through a 95 clamp can be screwed when it is necessary to withdraw the sections for uncoupling.

It is evident that changes in the construction and relative arrangement of the several parts might be made without avoiding my invention and hence I would have it understood

5 that I do not restrict myself to the particular construction and arrangement of parts shown and described, but,

Having fully described my invention, what I claim as new, and desire to secure by Letters 10 Patent, is—

1. In a shaft coupling, the combination with a pair of shafts the adjacent ends of which each have key-seats formed therein, of a collar having key-seats therein, and a series of 15 keys made to conform to the shape of the openings formed by the key-seats in the shafts and collar, and means for locking the keys passing through every two keys for holding the shafts against displacement, substantially 20 as set forth.

2. In a shaft coupling, the combination with a pair of shafts having key-seats formed therein, of a collar having key-seats therein, and a series of keys having bolt holes therein said 25 keys made to conform to the shape of the openings formed by the key-seats in the shafts and

collar, and a bolt adapted to be passed through the holes in each pair of keys, whereby the latter are drawn toward each other, substantially as set forth.

3. In a shaft coupling the combination with a pair of shafts the ends of which are provided with inclining key seats, of a collar in which the ends of the shaft are placed, keys fitted in each of the seats and means passing through every two keys for drawing the keys toward each other, substantially as set forth.

4. In a shaft coupling, the combination with a pair of shafts, and a collar, said parts each provided with key seats, of keys of unequal 40 lengths, located in the seats, the longer keys overlapping the ends of both shafts, and bolts passed through the keys whereby they are drawn toward each other, substantially as set forth.

In testimony whereof I have signed this specification in the presence of two subscribing witnesses.

DAVID BOORMAN.
